Federick F. Danback
ATTORNFYS

UNITED STATES PATENT OFFICE.

HARVEY C. MASLAND, OF PHILADELPHIA, PENNSYLVANIA.

EMERGENCY SURGICAL SPLINT.

Application filed July 27, 1922. Serial No. 577,810.

To all whom it may concern:

Be it known that I, HARVEY C. MASLAND, a citizen of the United States, residing in the city and county of Philadelphia, State 5 of Pennsylvania, have invented a new and useful Emergency Surgical Splint, of which the following is a specification.

My invention consists of an emergency splint composed of bendable strips that can 10 be slid on each other to give small bulk, and also provide for extension and rigid clamping together in such extension to accommodate any length of limb or arm that might be encountered.

15 It consists also of the provision of means for employing additional straps or bandages on the splint when so required.

The invention is satisfactorily illustrated in the accompanying drawing, but the important instrumentalities thereof may be 20 varied, and so it is to be understood that the invention is not limited to the specific details shown and described, as long as they are within the spirit or scope of the claims.

25 Figure 1 represents a side elevation of a surgical splint embodying my invention.

Figure 2 represents a perspective view of a detached member thereof.

30 Figure 3 represents a partial plan view, and a partial longitudinal section on line 3—3 Figure 1.

Figure 4 represents a perspective view of a clip employed for an additional strap or bandage.

35 Figure 5 represents a transverse section on line 5—5 Figure 4.

Figure 6 represents a view similar to Figure 1 showing certain parts in different adjusted positions and deflected.

40 Figures 7 and 8 represent perspective views of other forms of clips that may be employed.

Similar numerals of reference indicate corresponding parts in the figures.

45 Referring to the drawings.

1 and 2 designate opposite members of a splint, the same being formed of independent pairs each composed of a plurality of strips 3 and 4 of pliable metal or other 50 suitable material, which strips are placed side by side and connected by the brackets 5 with spaces therethrough through which said strips 3 and 4 are passed and movable (in conjunction or separately) for purposes 55 of adjustment of the length of the splint

relatively to the bone (or bones) that is fractured for which the splint is employed, said strips being engageable by the set screws 6 (or other suitable devices) which screws are fitted to said brackets and adapted 60 to have their points bear against either strip whereby the strips are pressed and clamped together and thus firmly held in their adjusted positions.

I prefer the collapsible splint members 65 in pairs opposed to each other on opposite sides of the limb, though a single collapsible splint member with the brackets and facilities for application to but one side of the fractured long bone is also possible. 70

I usually employ but two strips, but it is readily seen that an additional strip or more can be added. These could be slid together in small compass and yet drawn out and clamped together by the sleeve 75 brackets to make a sufficiently lengthy splint for any possible need.

The spaces in the brackets are made sufficiently wide to receive the strips 3 and 4 said brackets having on their sides additional spaces forming loops at 7 to allow of the insertion of the strap 8 which latter is adapted to be passed around the relative portion of the limb of the fractured bone or bones and to be properly held thereon by 85 the buckle 9 or other suitable means.

On the ends of the strips 3 and 4 are the elongated eyes 10 which may be bent down and up from the material of said ends or otherwise secured thereto and held tightly 90 in position by the rivets 11, said eyes having passed through them the straps 12 and 13 respectively which are provided with buckles 14 and 15 respectively by which means the end portions of the splints may be tightly 95 bound in position and retained thereat. The eyes 10 are provided with set screws 16 which are adapted to engage the straps 12 and 13 and so prevent displacement of the latter from their adjusted positions to any 100 required extent and as the strips are formed of pliable material they may be bent to conform with the surface of the limb to which the splints are applied.

Should additional straps be required, I 105 employ variably constructed separate clips such as shown at 17, Figures 4 and 5, at 18, Figure 7, and at 19, Figure 8, either of which may be fitted over the strips 3 and 4 and have such straps connected therewith. 110

set screws 20 being also fitted on said clips to tighten against the straps and retain them in their adjusted positions.

Having thus described my invention what I claim as new and desire to secure by Letters Patent, is:—

An emergency splint consisting of two opposed pairs of splint arm sets of bendable metal, each set being adjustable in length and adjustable independently of each other, each set being readily bendable in

emergency to fit the surface curves of a fractured part, terminal strap brackets at the distal ends of the opposing splint arm sets, straps for said brackets to hold the ends of the opposing splint arms set in adjusted position, and additional strap brackets adapted to be positioned along the length of the opposing splint arm sets for straps to bind a limb to the opposing splint arm sets at any desired position.

HARVEY C. MASLAND.
